UNITED STATES PATENT OFFICE.

AUGUSTE GILLIARD, OF LYON, FRANCE.

CLOSURE FOR BOTTLES AND OTHER RECEPTACLES.

No. 888,234.

Specification of Letters Patent.

Patented May 19, 1908.

Application filed June 7, 1907. Serial No. 377,775.

To all whom it may concern:

Be it known that I, AUGUSTE GILLIARD, a citizen of the French Republic, residing at Lyon, France, have invented certain new 5 and useful Improvements in Closures for Bottles and other Receptacles, of which the following is a specification.

Various devices are known for re-closing glass receptacles having thin necks and more 10 or less capillary orifices originally closed by the pointed termination of the neck, the latter being broken off for opening the orifice. Receptacles of this kind are used for containing volatile liquids, such as methyl 15 and ethylic chlorid, or mixtures of such liquids with other substances. Some of these known devices are defective or of such a nature that a considerable amount of time is required for opening and closing the receptacle, and others, known as automatic, render it necessary for the operator to keep his 20 finger pressed against a lever to keep the orifice open.

The object of the present invention is to 25 obviate the above disadvantages and provide a closing device which is more simple and can be more rapidly manipulated than the known devices referred to, and which can be applied either to a capsule stopper or to a 30 pivoted stopper.

The invention is illustrated in the annexed drawing, in which

Figure 1 represents one of the elements of the closing device, and Fig. 2 the neck of a 35 receptacle fitted with a sleeve and collar for the purpose of fixing thereto the stopper shown in Fig. 3 or that shown in section in Figs. 4 and 5, and Fig. 6 is a section on the line A—A of Fig. 4.

40 For making the closure an india-rubber stopper of special shape is used, to avoid the defective closing which may arise from the jagged edge of the broken glass if a simple disk is used. This stopper consists of a disk 45 *a* (Fig. 1) having a central hemispherical or slightly elongated boss *b* of considerably smaller diameter than the disk, this boss being adapted to fit tightly into the more or less capillary orifice to be closed.

50 The sleeve *g* may be of very thin metal fixed by means of cement to the shoulder and tapering, cylindrical or curved neck of the receptacle, the latter being, for example, a glass tube. This sleeve has at its vertical 55 part, above the flared part, a collar or annular

enlargement *c* (Fig. 2) which is provided with shallow vertical grooves on its outer surface.

The metallic capsule or cap *d* (Fig. 3) contains the stopper *a b*, which is fixed thereinto by suitable means. The cap has a plurality 60 of resilient projections *e* terminating in hooks or bent parts *f*.

For closing the receptacle after the point of the tube has been broken off the sleeve *g* is placed between the projections *e* of the cap 65 and the latter is thrust down until the hooks or bent parts *f* engage the collar *c*. The hemispherical boss of the stopper is by this means fastened down on to the orifice with a certain amount of pressure. 70

The receptacle can be re-opened by a sharp pull exerted on the cap to disengage the hooks *f* from the collar *c*.

It is frequently necessary that the operator should be able to open and close the receptacle with one hand. This can be done with the hinged stopper shown in Figs. 4 and 5, which also has the advantage that when the receptacle is open, with the stopper in the position shown in Fig. 5, the stopper retains 75 its position without being held by the operator. The stopper may be permanently connected to the sleeve on the neck of the receptacle, or may be detachable, the latter arrangement being, however, preferred. 80

The device shown in Figs. 4 and 5 comprises a vertical rib *h* having at or near its ends *i* and *j* two pairs of segmental arms *k* and *l*. Each pair of arms constitutes approximately three-quarters of a circle and 90 forms a spring clip. The upper arms *k* are flat and the lower arms *l* are vertically grooved or ribbed on their inner surfaces and approximately semicircular in cross-section.

To the upper end *i* of the part *h* a lid is 95 hinged by means of a pivot *m*. This lid comprises a cap *n* which is concentric with the spring clips and contains the india-rubber stopper *a b*. From the cap *n* projects an arm *o*, the free end of which is bent upwards 100 slightly. To this arm is fixed a spring *p*, which automatically holds the lid down when the receptacle is closed and retains it in the vertical position when the receptacle is open. The said spring may also be parallel with the rib *h*. 105

The arms or clips serve to secure the lid and stopper to the sleeve on the receptacle. The sleeve is inserted into the clips so that the lower rounded clip engages the collar *c* 110

on the sleeve, the sleeve being thrust against the rib *h*, so that it is firmly gripped. The grooves with which the collar *c* and lower clip are provided prevent too easy displacement of the parts.

For detaching the lid from the receptacle the latter is held in one hand, near the collar *c*, and the lid is gripped between the thumb and index finger of the other hand, and 10 pulled so that the upper clip is first disengaged. This is preferably done with the lid in the open position.

For opening the lid the receptacle may be held in one hand and the arm *o* and spring *p* 15 depressed with one finger, preferably the index finger, of the same hand, so that the lid is lifted into the vertical position and exposes the orifice, the arm *o* being then parallel with the rib *h* and remaining in this position as long as desired. For re-closing the receptacle the index finger is pressed against the upper part of the arm *o*, whereupon the spring *p* automatically closes the lid. The spring can of course be made of any desired 25 strength. The opening and closing can also be effected by actuating the arm *o* by means of the thumb, but this is less convenient.

The forms of construction of the closing device and means of attachment illustrated 30 in the annexed drawing are preferred on account of their cheapness, simplicity, convenience and lightness, but modifications thereof are possible. Instead of providing the receptacle with a collar or collars, a groove or 35 grooves may be provided for the same pur-

pose. The number of resilient projections or clips may be greater or smaller than shown in the drawing, and the clips may engage the sleeve vertically instead of horizontally.

The device may be used for closing receptacles of all shapes, having more or less capillary orifices or wide orifices, the dimensions, strength and shape of the parts being selected to suit each particular purpose.

What I claim as my invention and desire 45 to secure by Letters Patent of the United States is:—

1. A receptacle having a metal sheath inclosing a portion thereof, said sheath having a collar, an elastic stopper adapted to bear 50 in the orifice of the receptacle, a carrier containing the stopper, and means on the carrier for engaging with the collar to hold the stopper in place.

2. The combination of a receptacle, a 55 metal sheath inclosing a portion of said receptacle and carrying a grooved collar, an elastic stopper adapted to bear on the orifice of the receptacle, a spring-pressed pivoted carrier containing the stopper, and a plurality of clips in connection with the carrier adapted to secure same to the neck of the receptacle, one of said clips being grooved and engaging the grooved collar aforesaid.

In witness whereof I have signed this 65 specification in the presence of two witnesses.

AUGUSTE GILLIARD.
